HANDLE GRIP FOR MANUALLY STEERED DEVICES

Norman B. Williamson, Portland, Oreg., assignor to
Jarman-Williamson Company, Portland, Oreg.

Application April 9, 1956, Serial No. 40,985

Term of patent 14 years

(Cl. D10—8)

FIG. 2.

FIG. 1.

FIG. 3.

Fig. 1 is a bottom plan view of a handle grip for manually steered devices, showing my new design.

Fig. 2 shows the handle grip in end elevation.

Fig. 3 shows the handle grip in side elevation.

I claim:

The ornamental design for a handle grip for manually steered devices, as shown.
